US0D1007230S

(12) **United States Design Patent** (10) **Patent No.:** **US D1,007,230 S**
(45) **Date of Patent:** **** Dec. 12, 2023**

(54) **LID FOR BEVERAGE CONTAINER**

(71) Applicant: **ENI-JR286, Inc.**, Torrance, CA (US)

(72) Inventors: **Jesse C. P. Lee**, Torrance, CA (US);
George A. Patrikeyev, Santa Cruz, CA (US)

(73) Assignee: **ENI-JR286, Inc.**, Torrance, CA (US)

(**) Term: **15 Years**

(21) Appl. No.: **29/814,861**

(22) Filed: **Nov. 9, 2021**

(51) LOC (14) Cl. **07-01**

(52) U.S. Cl.

USPC **D7/392.1**; D7/396.2; D9/449

(58) **Field of Classification Search**

USPC D3/202; D7/213, 300, 300.1, 302, 303, D7/305, 314, 316, 317, 301, 7, 319, 320, D7/321, 322, 354, 358, 361, 387, 391, D7/392.1, 393, 394, 396.2, 397, 398, 399, D7/413, 414, 507, 509, 510, 511, 523, D7/601, 602, 605, 606, 607, 608, 615, D7/619.1, 620, 622, 629, 630, 633, 703, D7/705, 706, 707, 708, 708.1, 900, 392, D7/532; D9/434-447, 452, 453, 503, D9/516, 531, 719, 772, 905, 449, 450

CLAIM

The ornamental design for a lid for beverage container, as shown and described.

DESCRIPTION

FIG. 1 is a top perspective view of a lid for beverage container showing our new design.

FIG. 2 is a bottom perspective view thereof.

FIG. 3 is a front elevational view thereof.

FIG. 4 is a left side elevational view thereof.

FIG. 5 is a right side elevational view thereof.

FIG. 6 is a rear elevational view thereof.

FIG. 7 is a top plan view thereof; and,

FIG. 8 is a bottom plan view thereof.

The broken lines depict portions of the lid for beverage container that form no part of the claimed design.

1 Claim, 8 Drawing Sheets
